TUNING MECHANISM FOR RADIO RECEIVING APPARATUS

Ernest A. Zadig, New York, N. Y., assignor to
 Radio Corporation of America, New York,
 N. Y., a corporation of Delaware

Application July 10, 1929, Serial No. 377,151

14 Claims. (Cl. 250—40)

This invention relates to apparatus for tuning radio receiving devices and more particularly to apparatus for tuning radio receiving devices from a remote point.

5 Heretofore in the operation of radio receiving devices, it has been customary to tune the same by the manipulation of dials, etc., located about or secured to the casing containing the receiving device and connected to the tuning elements of 10 the receiver. In some instances, it is desirable that the actual receiving apparatus be located at a point remote from the listener and for this purpose it is desirable that some arrangement be provided for tuning this receiving device without 15 recourse to actual manipulation of the dials secured to the set.

Accordingly, an object of the present invention is to provide means for tuning a radio receiving set from a remote point.

20 The present invention provides an arrangement whereby a radio receiving set can be tuned from any point however remote from the actual set the listener may be. The apparatus for accomplishing this purpose consists in a source of 25 motive power for tuning the various apparatus to be moved during the tuning operation, which source of motive power is adapted to be controlled from any outside point. In perfecting this control, use is made of the usual interrupter type 30 signaling device commonly used in connection with automatic telephones.

Other features and objects of the invention will become apparent by reference to the following detailed description taken in connection with 35 the accompanying drawings wherein

Figure 1 is a perspective schematic view of a radio receiving device enclosed in a cabinet and having connected thereto the impulse generator through the agency of which tuning is accomplished;

Fig. 2 is an elevation of the source of motive power utilized in tuning the apparatus and the controlling mechanism thereto;

Fig. 3 is a plan view of the same device illustrated in Fig. 2;

Fig. 4 is an enlarged view of the arrangement shown in Fig. 3;

Fig. 5 is an enlarged perspective view of the dial showing the calibrations thereon and the 50 mechanism for controlling the source of motive power; and

Fig. 6 is a perspective view of one of the lugs attached to the calibrated dial.

Referring now to the drawings, 10 indicates 55 the cabinet of a radio receiving device of any

desired character having the usual tuning knob 11 and dial 12 which is calibrated for aiding in tuning the apparatus to the desired wave length. Inasmuch as the actual mechanism employed in the receiving device forms no part of the invention, it is not illustrated here in detail.

In Fig. 1, 13 indicates a device for causing interruptions in a closed circuit, such device being of the type commonly used in connection with automatic telephones. Inasmuch as these devices are well known in the art, the same is not described or illustrated in detail. Suffice it to say that upon movement of the dial in a counter-clockwise direction, the circuit connected therewith is opened and closed a number of times 15 corresponding to the distance traveled by the dial. In the present instance, the member 13 is shown connected to the receiving apparatus through a pair of lines 14. Passage of current through lines 14 and device 13 is controlled by 20 switch 59 and indicated by pilot light 51. If desired current for operating the set may be controlled by switch 50 in the same manner.

Mounted within the casing 10 at any desired place is a source of motive power; in the present 25 instance, an electric motor 15 which is geared to the shaft 16, upon which the dial 12 is frictionally mounted, through reduction gears 17 and 18. By the use of these reduction gears, it is possible when the motor 15 is energized to turn the shaft 30 16, which shaft 16 serves as a common shaft for the apparatus utilized in tuning this receiving device. This apparatus may be a train of condensers or any other type of mechanism desired, and is represented diagrammatically in Fig. 1 and 35 labeled "tuning reactors".

Secured to the dial 12 at spaced intervals are a number of lugs 19 which extend therefrom an even distance. Depending from each of these lugs 19 is a trip member 20 spaced at different 40 intervals from the ends of the respective lugs. The necessity for this spacing will be apparent hereinafter, but it should be noted that they serve to control the apparatus for different stations. The lugs 19 will be secured to the dial 45 12 at points thereupon which correspond to the points at which different broadcasting stations are usually received.

Secured within the casing 10 in any convenient place (in the present instance, on the motor casing 15) is a selector member 21 in the shape of a bar slidable between two guide members 22 and 23. In the present instance, this bar 21 is of square shape though it may be rectangular or any shape desired.

Extending centrally through the bar 21 is a rotatable shaft 24 from which extends an arm 25 through an opening near one end of bar 21. Near the other end of the bar 21 is a second opening 5 which permits the securing to the shaft 24 of a crank 26, the latter preferably being shown as integral with shaft 24, an arm 27 extending through a slot in a pawl member 28. The arm 27 is pivoted at one end thereof to crank 26, and its other end is free to move horizontally in a 10 backward and forward manner in the slot, a knob 27' on the end thereof preventing withdrawal from the slot. One side of bar 21 is cut away to provide a rack 29 made up of a number of teeth. 15 Mounted adjacent to the bar 21 is an electromagnet 30 having core 31. Pivoted above core 31 is an arm 32, the end 32a of which serves as a pawl member for advancing the bar 21 through the guides 22 and 23. This arm 32 is forced normally toward the dial 12 by means of a spring 33, its movement in this direction being limited by a stop 34. The pawl member 28 previously referred to has an angular extension 35 which, due to the fact that the member is pivoted about 20 the point 36, can be forced into engagement with the teeth of rack 29 by means of the spring 37 pressing against the upper end of member 28.

Pivoted to the rear of member 28 and about the point 38 is a switch bar 39 provided with a 30 contact point 40 co-operating with a contact 41 to control the circuit of motor 15. This contact bar 39 is normally forced toward a position to close the contacts 40 and 41 by means of a spring 42. The end of the bar 39 remote from contact 35 40 is provided with a cam shoulder 43 against which the end 28' of member 28 is adapted to press when the same is rotated about its pivot. A second switch composed of contact members 52 and 53 controls the flow of current either to the 40 entire set or only to the loud speaking instrument as desired. This switch is normally closed, being opened only during mechanical tuning.

A stop 44 secured to bar 21 and against which the end of bar 39 rests serves to prevent the 45 closing of contacts 40 and 41 when the bar 21 is in its position most remote from the dial 12. Spring 45, one end of which is secured to stop 44 and the other end of which is secured to guide 23 at the point 46, serves to withdraw the 50 bar 21 from dial 12.

Having described the mechanism embodied in the invention, the operation of the same is substantially as follows:

The set will be tuned manually, that is, the 55 apparatus associated with the dial 12 will be moved to a proper position corresponding to the station from which broadcast waves are to be received. With the apparatus and dial 12 in the proper tuned position one of the lugs with its 60 trip secured thereto will be fastened to the dial at the proper station number. The lug may be inserted through the opening 54 in the plate secured to the front of the cabinet and then fastened to the dial in any desired manner such as by 65 means of small set screw. This manual tuning of course is made possible due to the fact that the motor drive for the dial and associated apparatus is a frictional drive.

After lugs have been fastened to the dial in 70 positions corresponding to the points thereof at which different broadcast waves are received the set is in condition to be tuned mechanically.

Each of the lugs 19 is provided with a trip 75 20 which is spaced at varying distances from the ends of the lugs. For example, the lug 19 which

in Fig. 5 is shown approximately opposite the number 20 on the dial 12, is provided with trip member 20 near the free end thereof. The next lug approximately opposite the number 30 is provided with a trip 20 which is a slight distance 5 closer to the dial than the preceding trip and so on around the dial.

Current for operating the set may be supplied thereto from any desired source, the supply being controlled by switch 50. As soon as the circuit 10 from the source to the set is closed through this switch the same will be indicated by the pilot light 51 which indicates that the magnet 30 is energized rendering the mechanical tuning equipment in condition for operation. 15

With the interrupter 13 connected in the circuit of the electromagnet 30, which is normally energized, impulses or interruptions of the flow of current through the magnet can be produced by rotation of the dial of this interrupter. For example, should it be desired to tune in a station for which the dial 12 is normally turned until the indicator on the set reaches the point 40, the interrupter 13 will be operated by placing a pencil or other similar device in the opening numbered 3, rotating the dial clockwise to the stop, and releasing the same. As the dial rotates counter-clockwise, three interruptions in the current flowing through electromagnet 30 will be produced. When the circuit is broken, de-energizing 30 the magnet, the spring 33 pulls arm 32 in the direction of the dial. As this arm moves towards the dial and before it reaches stop 34, it engages one tooth of rack 29 and moves it and the bar 21 toward the dial 12. As soon as the circuit is 35 completed again, the bar 32 is attracted again to the magnet, but the bar 21 is held in this advanced position by engagement of the point 35 with one of the teeth of rack 29. The succeeding impulses or interruptions in current flow 40 through the magnet cause the advancement of bar 21 a distance corresponding to the number of teeth advanced by pawl 32. In the example of this illustration, the number of teeth by which the bar 21 will be advanced is three. As soon as 45 bar 21 moves from its normal position, spring 42 forces bar 39 about its pivotal point and contacts 40 and 41 are closed, thereby energizing the motor 15, which upon rotation moves the dial 12 and the apparatus associated therewith. Simultaneously with the closing of contacts 40 and 41 contacts 52 and 53 are opened breaking the power circuit to the entire set or to the loud speaker as the case may be for the purpose of preventing confusing signals being received as the set is 55 tuned through undesired broadcasting bands.

This rotation of the dial continues (due to the motor 15) until arm 25 has moved into the path of the trip 20 secured to the lug 19 opposite number 40. When the arm 25 comes into contact with the trip 20 and the motor 15 causes continued rotation of dial 12, the arm 25 is forced to follow this rotation somewhat due to the length of the finger portion 25', thereby imparting a slight rotary movement to the shaft 24 to which the arm is secured. Upon rotation of the shaft 24, the member 28 is rotated about its pivotal point due to the crank 26, arm 27 of which has been moving upwardly along member 28 through the slot provided therein. Rotation of this member 28 produces two instantaneous results, one of which is to release point 35 from contact with the teeth of rack 29, thereby permitting the spring 45 to retract bar 21, and the other result of which is to cause the end of member 28 to ride up 70 75

shoulder 43 of bar 39, depressing the same and opening the motor switch, through contacts 40 and 41. More particularly this operation may be explained as follows: A trip 20 is intercepted by the finger 25' of arm 25, the shaft 24 is angularly displaced thus moving the link 27 backward and rotating the dog 35 about the pivot 28. This results in the raising of dog 35 and the lowering of the edge 28' into that position wherein it is prevented from returning to its spring pressed normal position by the abutment 43. It remains in this position until the spring 45 has retracted the bar 21 and rack 29 to its normal position prior to dialing operation, at which normal position the pin 44 strikes the portion of the switch 39 in its path, and releases the edge 28', thereby permitting the spring 37 to press the dog 35 into contact with the rack 29, thus preparing the entire mechanism for a complete renewal of the cycle of operation.

As shown in Figs. 2 and 3 particularly, the position of the mechanism is shown at the instant when the entire cycle has been completed, after the pin 44 has released the edge 28' from the abutment 43, and has made the mechanism receptive for a new dialing operation. Naturally, when these contacts 40, 41 are opened, the dial 12 is no longer rotated and the apparatus of the receiving device stays at the point of tuning desired. The controlling mechanism having been returned to its normal position, the set may be tuned for any other station desired by manipulating the interrupter 13 in the manner before explained.

In the event the dial 12 and the tuning apparatus associated therewith are not rotatable through 360° but only through 180° switches may be provided at diametrically opposite points for reversing the direction of rotation of the motor. For actuating these switches (which are not illustrated) use may be made of a trip member 55 located upon and secured to the inner face of the dial 12. It will be evident that the operation of this arrangement is: The dial and associated mechanism will be rotated until the proper point is reached even though it may be necessary to reverse the direction of movement due to the fact that the dial has already rotated past the point of desired reception.

It is to be understood that the present invention is not to be limited to the embodiment illustrated, but is to be limited only by the appended claims.

I claim:

1. The combination with the tuning elements of a radio receiving system of a driven member associated therewith, a source of electromotive power for driving said member, selective control mechanism for said source activated by interruptions in current flow therethrough, means responsive to adjustment of the driven member to a predetermined position, for actuating the control mechanism to render the source inoperative at said position, and means for causing interruptions in current flow through said control mechanism.

2. Means for tuning a radio receiver comprising the combination of a shaft, a plurality of tuning reactors mounted thereon, a drum member associated therewith and having a number of trip members secured about the periphery thereof at different positions, a source of electromotive power for driving said member, a control member for said source having a part movable into the paths of said trip members, and means

for selectively causing the advancement of said part into the path of a predetermined one of said trip members to actuate the control member to render the source inoperative.

3. The combination with the tuning reactors of a radio receiving system of a driven member associated therewith and having a number of trip members secured thereto at different positions, at least two of said trip members having securing means arranged so that they may be angularly adjusted about the periphery of said member, and a source of electromotive power for driving said member, a control member for said source having a part movable into the paths of said trip members, means for selectively causing the advancement of said part into the path of a predetermined one of said trip members, and means operable upon contact of said part with one of said trip members to cause deenergization of said source and for returning said part to normal position.

4. In combination, a radio receiving set, a station selector remote from the set, means for tuning the set to a desired station, a motor actuated means for varying said tuning means, control means connected with said remote selector for rendering said motor actuated means operative, a rotatable dialing means rotatable through a predetermined angle according to the desired station associated with the selector for remotely determining the operation of said control means at a desired station position of said tuning means, and means associated with the latter adapted to cooperate with said control means for automatically rendering said motor actuated varying means inoperative at said position, said varying means being rendered operative only after said control means operation position has been determined by the dialing means.

5. In combination, a radio receiver, a station selector remote from the receiver, means including a variable reactance for tuning the set to a desired station, an electrically actuated means for varying said tuning means, control means connected with said remote selector for rendering said actuated means operative, a rotatable dialing means associated with the selector for remotely determining the operation of said control means at a desired station position of said tuning means, a stop for limiting the angular rotation of said dialing means, and replaceable stops mounted on the tuning means adapted to cooperate with said control means for rendering the electrically actuated varying means inoperative at said station position, said varying means being rendered operative after said control means operation position has been determined by the dialing means.

6. In combination, a radio receiver, adjustable reactance means for tuning the receiver to a desired station, an electrically operated means for varying the tuning means, control means for said varying means, and a rotatable dialing means remote from said receiver connected to selectively actuate said control means for rendering said varying means operative, and replaceable stops on said tuning means adapted to cooperate with said control means for rendering said varying means inoperative at predetermined dial points corresponding to said stops, at least two of said stops being arranged to be angularly adjustable with reference to said tuning means.

7. The combination with the tuning elements

of a radio receiving system of a tuning shaft, a plurality of replaceable tripping members mounted on said shaft, a power means for driving said shaft, an intermittently actuated control including a switch for rendering said power means operative, and a remote station selector electrically connected to said intermittently actuated control means for selectively positioning the same in the path of a predetermined one of 10 said members.

8. The combination with the tuning shaft of a radio receiver, of an indicating drum mounted on said shaft, a plurality of trip members mounted on said drum at different station positions, at least two of said trip members being angularly adjustable about the periphery of said drum, an electrically actuated means for driving said shaft, a control member for said driving means including an element movable into the paths of said trip members, a station selector dial electrically connected with said driving means and control member for selectively causing the advancement of said movable element into the path of a predetermined one of said 20 trip members and means for limiting the extent of motion of said dial to a predetermined amount.

9. In combination, in a radio receiver, a rotatable tuning shaft, a plurality of adjustable members associated therewith in different station positions, means for actuating said shaft, means including a member mounted for longitudinal and angular movement for controlling the operation of said shaft actuating means, and additional means remote from the receiver for selectively positioning the last mentioned member in the path of a predetermined one of said 35 adjustable members to render said shaft actuating means inoperative at a position of the tuning shaft corresponding to one of said station positions.

10. In combination, in a radio receiver, a rotatable tuning shaft, a plurality of adjustable members associated therewith in different station positions, means for actuating said shaft, means, including a tripping member, for controlling the operation of said shaft actuating means, and additional means remote from the receiver for selectively positioning said tripping member in the path of a predetermined one of 45 said adjustable members to render said shaft actuating means inoperative at a position of the tuning shaft corresponding to the desired station position.

11. Tuning apparatus for radio receivers and the like comprising a member associated with the said radio receiver so that movement thereof will cause a tuning element of said receiver to be adjusted, a plurality of position determining elements arranged to move as said member is moved, each of said position determining elements having a part thereof adapted to follow a

path which is different from the path followed by the corresponding part of each of the other elements, a member movable progressively into each of said paths, means for controlling the progressive movement of said member whereby it may be stopped in a predetermined one of said paths, mechanism for causing movement of the first mentioned member, and mechanism actuated by said member movable progressively into said paths for causing the first mentioned member to stop at a predetermined position. 10

12. Tuning apparatus for radio receivers and the like comprising a rotatable element associated with a tuner of the said radio receiver for movement therewith, a plurality of members arranged to rotate with said element, each of said members being provided with a contact area, said areas being located so that each area follows a path which is parallel to the paths of the other areas, means movable progressively into each of 15 said paths, mechanism for controlling the progressive movement of said means whereby it may be stopped in a predetermined one of said paths, mechanism for rotating said element, and mechanism actuated by said means for causing said 20 element to stop at a predetermined position.

13. Tuning apparatus for radio receivers and the like comprising means associated with the said radio receiver so that movement thereof will adjust a tuning element of said receiver, a plurality of position determining elements arranged to move with said means, each of said position determining elements having an actuator adapted to follow a path which is different from the path followed by the actuators of the other elements, a 25 member movable progressively into each of said paths, a rack and pawl mechanism for advancing said member progressively whereby it may be stopped in a predetermined one of said paths, mechanism for causing movement of the first 30 mentioned means, and mechanism actuated by said member for causing the first mentioned means to stop at a predetermined position.

14. Tuning apparatus for radio receivers and the like comprising a tuning dial, a plurality of members secured to said dial for movement therewith, each of said members having a projection located so that it follows a path which is different from the path followed by the projection on each of the other members, an element 40 movable progressively into each of said paths, manually operable means for controlling the progressive movement of said member whereby it may be stopped in a predetermined one of said paths, mechanism for rotating said tuning dial, 45 and mechanism actuated by said element when it contacts with one of said projections for causing the tuning dial to stop at a predetermined position.

ERNEST A. ZADIG. 60
